UNITED STATES PATENT OFFICE.

EMIL ZBINDEN, OF SOLOTHURN, SWITZERLAND.

TIME-SWITCH-ACTUATING MEANS.

Application filed April 5, 1926, Serial No. 99,861, and in Switzerland April 16, 1925.

This invention relates to a device for automatically shifting according to time curves, those adjustable contact-members of time switches which determine the periods of time 5 of making and breaking the circuit.

According to my invention a time switch actuating mechanism embodying my invention is provided, which comprises at least one set of worm gearing connected with a clock-work mechanism, the driving wheel of which worm gearing makes one revolution per annum and whose individual teeth are so formed that when in juxtaposition they follow a desired time curve, and the other 10 driven wheel of the worm gearing transmits the forward and backward movements imparted to it by the driving wheel to an adjustable contact member of the time switch which effects the making and breaking of a 15 circuit, such as a lighting circuit, in the course of a year according to its position and corresponding to the time change arrangements of the circuit-closing and circuit-breaking points occasioned by the course of 20 the time curve.

Preferably, the device comprises a plurality of worm gears, one having teeth corresponding to a lighting curve, namely, a plot of time periods for making or breaking, or both making and breaking an electric light circuit, and the other teeth corresponding to other time 25 curves.

Conveniently, the device is driven by the main spring of the clockwork mechanism of 30 the time switch.

The invention consists in the construction, arrangement and combination of parts described hereinafter and pointed out in the claims.

One embodiment of the invention is illustrated by way of example in the accompanying drawings, wherein:—

Figure 1 is a vertical section through one form of device according to the invention,

Figure 2 is a plan view thereof, and

Figure 3 is a development of the periphery of the driving worm gear.

Figure 4 is a face view of a type of switch device which may be actuated by the switch 50 actuating mechanism.

Figure 5 is a sectional view of the same.

The device comprises shifting means for use in connection with means for actuating a contact device of a time switch of known 55 kind, such as is described for example in the Swiss patent specification No. 114,176.

On the annular base 1, of insulation, of this contact device is mounted a cylindrical casing 2 in which is arranged the spring barrel 3 of the clockwork mechanism of the time switch. The spindle 4 which serves for winding up the main spring is driven by the shaft 5. Fast on the upper end of the spindle 4 is an eccentric 12 which actuates a pawl 6 engaging with a crown wheel 7. This wheel 60 is fast on one end of the vertical shaft 8 located outside the casing, the other end of which shaft carries a pinion 9 meshing with the teeth 10 of a drum 11 rotatable on the casing 1. The pawl 6 turns the wheel 7 one tooth per diem and the gear ratio of the pinion 9 and tooth 10 is so selected that the drum 11 rotates at the rate of one revolution in one year.

In the illustrative embodiment the drum 75 11 has on its periphery four rings 13 arranged in parallel relation, each of which is intended to operate as a worm gear and has at its periphery teeth arranged according to a predetermined time curve. The teeth of the first 80 ring of the series which are arranged according to a lighting curve, are shown developed in Figure 3. This development may be produced by forming and arranging the teeth in such a manner that in the orbit of rotation of 85 the gear they follow a time curve of periods for circuit making and breaking actions. As Figure 3 shows, the teeth not only differ in pitch, but some of them are directed in the opposite direction to others.

The other rings indicated only in broken lines in Fig. 1 are provided with teeth arranged according to other time curves, for instance light extinguishing and light tariff 90 curves.

With each worm gear meshes a pin wheel 14, journaled on a convenient part of the casing 2. Each pin wheel has two rings of pins or teeth 15 and 16 in planes at right angles to one another, the one ring 15 meshing with the allotted worm wheel, while the ring 16 serves for transmitting the movements of the worm wheel to a vertical shaft 17. These shafts 17 carry each at their opposite ends pinions 17^a and 17^b of insulating material, the pinion 17^a meshing with the toothed rim of a contact ring 18 adjustably mounted on the insulated annulus 1, and the pinion 17^b meshing with the ring 16, each worm wheel 13 is thus operatively connected in this manner with one of 100 the contact rings 18 and in the course of a year 105 adjusts it exactly corresponding to the time 110.

curve represented by the teeth of the allotted worm wheel.

As stated, the switch actuating device is employed for automatically shifting according to time curves those adjustable contact members of time switches which determine the periods of time of making and breaking a circuit. The term "time curve" includes lighting and extinguishing curves, and tariff curves. These curves are based upon the variation of the length of days during the year according to geographical latitudes. The lighting circuits, in which lamps are cut in or out in accordance with such time curves, the times for lighting the lamps or extinguishing them are plottable in curves, and these are known as lighting or extinguishing curves, respectively. If the time controller switch is to cut in or out a boiler, for instance, in addition to controlling the lights, and the boiler is to be cut in only during the day time, when the current is sold at the lowest tariff, then the cutting in and cutting out curves for the boiler must correspond to the determined time curves. In such case the boiler cutting in curve will correspond with the light extinguishing curve and the boiler cutting out curve will correspond to the light switching in curve. This is what is known as a tariff curve. The worm gears of the actuating device are designed to operate or control the contact elements of a time switch in accordance with such curves, and the teeth of each worm gear are accordingly set according to the plot of the curve for shifting the pin wheel actuated thereby either in a forward or a backward direction, as required in accordance with the curve, to shift the working parts of the time switch accordingly.

In Figures 4 and 5 I have shown sufficient of a time switch having contacts for controlling a circuit for enabling the operation of the switch actuating mechanism to be readily understood. In these views, in the insulating annulus 1, which serves at the same time as the clock face, there are rotatably journaled, one behind the other, the two metal rings 18 and 19, well insulated from one another, and whose inner edge extends in a spiral line. On each ring thus there is formed an offset 20 and 21 respectively. As long as these offsets cover each other, the contact arm 23, fixed to the hand 22 and extending across all contact rings (there may be more than only the two shown by way of example), will remain in contact with the ring 19, since the latter is of smaller diameter than the ring 18. If, however, by means to be described further down, the rings are relatively displaced so that their offsets 20 and 21 coincide with different sections of the clock face, the contact arm 23, upon slipping off the offset 21 of ring 19, will contact with the ring 18 and remain in this condition until it slips off its offset 20, whereupon it will contact with

another ring (not shown). On each ring slides a contact member 24 fixed on the annulus 1 (only one such contact member 24 is shown). The direction of the current is indicated by the arrows 25 and 26.

If, as shown in Figures 4 and 5, the rings have different inner diameters, it is possible, by properly adjusting two or more of these rings so that their respective offsets register exactly, to eliminate one or more completely for correspondingly varying the number of the switching operations.

If, for instance, each ring is connected to a group of lamps, it is possible, by adjusting the several rings in the manner described, to cut out one or more such lamp groups for required periods. A change in the succession of the switching operations in the case of rings presenting inner diameters of different extent is not possible, for the reason that within 24 hours the contact member 23 can always only slip from rings of smaller diameter to those of larger diameter.

However, all rings may also have the same diameter, as shown in Figure 1, in which case it is not possible to bring two or more rings into perfect registry, since in that case the member 23 will simultaneously contact with two or more rings, when the device, obviously, would become inoperative. In the case of rings of equal diameters, then, the number of the switching operations is not variable, but their sequence is.

I claim:—

1. In a time switch actuating device, the combination with a movable member for controlling a circuit, a driving worm gear whereof the teeth are so formed that when in juxtaposition they follow a time curve, a driven worm gear that meshes with the said driving worm gear and is operatively connected with said movable member, and mechanism for rotating said driving worm gear at the rate of one revolution per annum, substantially as described.

2. In a time switch actuating device, the combination of a plurality of circuit-controlling members, a plurality of pairs of worm gears, one pair allotted to each controlling member, and comprising each a driving worm gear and a driven worm gear meshing therewith, mechanism for rotating the driving worm gears each at the rate of one revolution per annum and means operatively connecting the driven worm gears each with the controlling members, said worm gears having teeth arranged for motion transmitting actions at different predetermined time periods.

3. In a time switch actuating device, the combination of clockwork comprising a main spring, a circuit-controlling member, worm gearing comprising a driving worm that is arranged to be driven by said main spring at the rate of one revolution per annum and having its teeth arranged in a path for

transmitting clockwise or counterclockwise motion to a part to be driven thereby at predetermined periods in a single direction of movement of said driving worm, and a driven worm gear that meshes with said driving worm gear and is operatively connected with said controlling member, substantially as described.

4. A device for automatically operating 10 adjustable contacts controlling the cutting in and cutting out time periods of time switches according to time curves, comprising at least one worm wheel unit driven by clock work mechanism whose driving pinion makes one 15 revolution per year, and a driven wheel operated by the worm wheel unit for transmit-

ting motion to said adjustable contact, the teeth of the worm wheel unit being arranged to extend on a course corresponding to a desired time curve and adapted to transmit forward or backward movements to the driven wheel for correspondingly actuating the adjustable contact members of the time switch, whereby according to positions of the contact members and of the teeth of the worm wheel unit the members will be operated for cutting in and cutting out actions at predetermined periods in the course of a year.

Signed at Bern, this 24th day of March 1926.

EMIL ZBINDEN.
